UNITED STATES PATENT OFFICE.

OSCAR C. RIXSON, OF NEW YORK, N. Y.

DEVICE FOR OPERATING TRANSOMS AND CASEMENTS.

1,171,979.

Specification of Letters Patent. Patented Feb. 15, 1916.

Application filed November 19, 1914. Serial No. 872,877.

To all whom it may concern:

Be it known that I, OSCAR C. RIXSON, a citizen of the United States, residing at the city of New York, in the borough of Manhattan and State of New York, have invented certain new and useful Improvements in Devices for Operating Transoms and Casements, of which the following is a full, clear, and exact description.

10 This invention relates to operating mechanism for swinging closures and particularly for casements and transoms, and has for its primary object the provision of an operating mechanism of this character 15 which is of a simple and compact construction lending itself admirably for use where it is desired to conceal such mechanism within the window frame or door casing.

Other objects of the invention are to provide a mechanism which is positive in operation, capable of being readily and easily manipulated and by which the windows, transoms or the like are held in any desired position without the aid of latches or other 25 fastening devices.

With these and other objects in view, which will be obvious to one skilled in the art from the detailed description hereinafter to follow, my invention consists of the constructions and combinations which will be hereinafter described and particularly pointed out in the appended claims.

In the accompanying drawings:

Figure 1 is a plan view of a portion of a window frame having associated therewith one form of my improved construction, the stool of the window frame being removed to more clearly show the operating mechanism; Fig. 2 is a vertical section through Fig. 1; Fig. 3 is an enlarged view of the operating mechanism, the same being shown apart from its connection with a window; Fig. 4 is a vertical section through a door casing showing my improved mechanism associated with a transom; and Fig. 5 is a vertical sectional view taken at right angles to Fig. 4.

Referring first to Figs. 1, 2 and 3, wherein there is shown the actuating mechanism associated with a window frame and casement of the usual type, 1 designates the sill of the window, 2 the apron or trim, and 3 the stool which is spaced from the sill by means of a block 4 to leave a recess or chamber *a* which is adapted to receive the actuating mechanism as will be hereinafter described.

A hinged window or casement 5, only a portion of which is shown, is of the usual type and is pivoted as at 6 to the window frame or casing 7. A stop 8 of the ordinary construction may be secured to the inner portion of the window frame. As is shown, the window 5 is adapted to swing outwardly on its hinge 6, which is accomplished by means of the actuating mechanism which will now be described. Inset in the inner face of the bottom strip of the window sash is a plate 9, carrying an angularly projecting finger 10 which is substantially flush with the bottom of the sash, which finger projects into the chamber *a* when the window is closed, and carries at its outer or free end a pivotally mounted roller or block 11 of fiber or any other desired material, which is adapted to ride in a slot in the bottom face of a tubular member 12, which is substantially rectangular in cross section. The outer end of this member is closed by a cap 13 which will prevent the roller or pin 11 from leaving the slot, while the other end is forced over the end of a solid lever 14 and forms a rigid continuation of the same.

The lever 14 is pivoted as at 15, to a base plate 16, which is secured to the sill in the chamber *a* and rising from the base plate is a casing or housing 17 into which one arm of the lever extends, the casing being so shaped that it will not interfere with the movement of this lever to its fully opened position as is shown in dotted lines. In the interior of this housing is positioned a screw or threaded shaft 18, one end of which is of reduced diameter, and is rotatably mounted in a recess in a plug 19, which is threaded into a suitably shaped aperture 95 or opening in one of the walls of the housing. The other end of the screw is also of reduced diameter and passes through a suitable bearing in a boss 20. Steel washers 21 and 22 preferably are provided at each end of the threaded portion of the screw to take up its end thrust, the length of screw between the washers being such that there will be no free play of the same. Mounted upon the screw 18 is a traveling nut 23 and it may here be stated that since this nut is subjected to severe strains in the opening and closing of a window, it is preferable to utilize a double thread so as to provide a large bearing surface for the nut without decreasing the pitch of the screw and the nut may travel rapidly from one end of the

screw to another upon rotation of the same. Projecting from this traveling nut is a radial lug 24, to which are pivoted links 25 which extend to and are connected at their 5 other ends, as at 26, to the end of the actuating lever 14 so that when the nut travels along the screw, its motion will be communicated to the lever and the block 11 will ride in the slot in the member 12 to cause 10 the window to open or close. As will be clear from Fig. 1, a squared end 27 of the traveling screw extends through a suitable aperture in the apron or trim 2 of the window frame, so that a crank handle 28 may 15 be readily applied to the same when it is desired to open or close the window, the other parts of the device, however, being located in the chamber *a* and thus concealed from view. Since the device described is 20 compact in construction, it is adapted to be readily positioned under the stool even in the existing forms of window frames. Assuming that the window is closed and that the actuating mechanism is positioned 25 as is shown in full lines in Fig. 3, the screw is rotated in a counter-clockwise direction, which will cause the traveling nut 23 to approach the other end of the screw. Since the link in its normal position is substantially 30 parallel to the axis of the screw, the force which is exerted on the end of the actuating lever through the link will be substantially parallel to the direction of line of travel of the nut and for this reason the 35 window is readily opened and as the window swings out, due to the eccentric mounting of the actuating lever and the window sash, the block 11 will ride outwardly in the slot in the member 12 increasing the leverage of 40 the actuating lever on the window as the latter opens, from which position it may be closed by the reverse operation. It may here be remarked that whether the window is closed or in any of its open positions, the 45 use of a traveler and screw of this character will maintain the window in a fixed position without the use of any latches or any other holding devices, as the traveling nut can only be displaced by the rotation of the 50 screw.

Referring now to the construction shown in Figs. 4 and 5, wherein I have disclosed a similar actuating mechanism for operating a transom, the jamb of the door in these 55 views is designated 30, the side trims of the door casing 31 and 32, respectively, and the buck or post to which the jamb and trims are secured, 33, the jamb being spaced from this post a sufficient distance to leave an 60 intervening space *b*, which extends vertically the entire height of the door casing, and in the form illustrated extends above the lintel bar 34 and the transom 35, only a portion of which is shown, which space is adapted to receive the actuating mecha-

nism for the transom so that it is entirely concealed from view. The transom is pivoted adjacent its bottom on one side thereof by any usual construction (not shown) and on the other side by means of a plate 36 which is inset into the side edge of the transom sash and to which there is secured a pivot 37, the same consisting of a cylindrical pin having a centrally disposed opening therethrough through which a screw 38 is 70 adapted to pass, the plate being countersunk at 39, for the head of this screw. The pivot pin 37 carries projecting lugs 40 in its end face which are adapted to fit into correspondingly shaped openings in the 75 plate so as to rigidly secure these parts together. The other end of the pin has rigidly secured to it a crank arm 42, which is positioned in the space *b*, by means of 80 43 which fit into correspondingly shaped 85 openings in the crank arm, the crank arm being held against the pin by a nut 44, which is threaded onto the end of the screw 38. The pivot pin 37 rotates in a brass bushing 45, which passes through the jamb of the 90 door. A long narrow substantial plate 46 is positioned in the chamber *b* by nuts 47 threaded on the ends of screws 48 passing through the jamb and suitable openings in the plate which nuts firmly clamp the plates 95 against the inner face of the jamb. The upper end of plate 46 is provided with a suitable aperture through which the end of the bushing 45 passes, these parts being secured together by a screw 48 passing 100 through the jamb of the door. The lower end of the plate 46 is bent angularly to form a seat and has riveted or otherwise secured to it a U-shaped yoke 50 which in the 105 assembly of the parts would be substantially 110 on the level of the door knob of the door, it being understood that in the drawings the parts are foreshortened by omitting vertical sections of the parts so that they may be clearly shown on an enlarged scale. This yoke which is of a width to fit between the side trims 31 and 32 of the door casing, forms the supporting structure for a screw 51 similar to the one heretofore described. One end of the screw rotates in a suitable 115 bushing 52 threaded into an opening in one of the upstanding sides of the yoke, while the other end has secured to it a cylindrical piece or sleeve 53 which is suitably supported in a similar bushing 54, the sleeve 53 120 passing through a suitable recess in one of the side trims of the door casing and having a centrally disposed squared recess in its outer end which forms a socket for a crank handle. Mounted upon this screw, as in the first form illustrated, is a traveling nut 55 which has also secured to it between its two spaced lugs, a link 56. The other end of the link is pivoted to a bell-cranked lever, which is pivotally secured 125 130 to the transom 35.

to the plate upon a pin 57, the arm 58 of the bell-crank lever to which the link 56 is pivoted being preferably bent to permit the remaining portion of the lever to lie substantially flat against the plate 46. The other arm 59 of the bell-crank lever is connected by means of a rod 60 to the crank arm 42. An escutcheon plate 60' is secured to the side trim of the door casing and has an opening therein through which the squared end of a hub-shaft 61 of the operating crank may be inserted into the socket in the sleeve 53. The crank arm 62 is pivoted to this hub-shaft as at 63 while secured to the inner face of the arm is a cushion 64 of rubber or other soft material. If the crank arm should be inadvertently left in a horizontal position extending into the path of swing of the door, the latter in opening will strike against the cushion 64 and swing the crank arm out of its path, thereby preventing breakage or injury of the parts. The operation of the form of the device shown in these two views is similar to that already described; by rotating the screw 51 the traveling nut 55 may be caused to travel from left to right which will, through its link connection, raise the outer arm 59 of the bell-crank lever and hence swing the transom on its pivot outwardly as is shown in dotted lines. It will be seen, however, that in this construction, when the transom is in its open position, the force necessary to close the same is greater than when it is in closed position and this is compensated for by so proportioning the link and its position with reference to the bell-crank that as the transom swings to its open position, the link swings farther away from the screw so that the travel of the nut along the screw to swing the transom through the same angular displacement is greater. This is clear from Fig. 4 wherein the dotted line position shows the half open and fully opened positions of the transom. To move the transom from its fully open position toward an intermediate position, the nut is therefore forced to travel a greater distance along the rotating screw and since the force applied to the crank handle may be regarded as constant, the power will be increased. This additional power will also be supplied in operating the casement and would be more apparent if the window were designed to swing through an obtuse angle in which instance the link would then move farther away from the screw similar to the operation of the link shown in the transom operating mechanism, it being understood that the length of the screw would be increased the necessary amount to give the greater angular displacement. In both forms, therefore, additional power may be supplied in the initial movement of the swinging closure from its fully open position and depend-

ing upon the angular displacement of the pivoted link from its position parallel to the threaded shaft or screw.

The transom may be pivoted adjacent its upper edge instead of along the bottom which would only require the position of the traveling nut to be changed so that when the transom is closed, the nut stands at the right end of screw instead of at the left end as it is now shown.

While I have shown my invention in two of its chief embodiments, yet it is obvious that the structure of the casement and transom shown is by way of description only and not by limitation, as it is possible to use a device of this character with all forms of swinging closures, and it is not my intention to be limited to the particular constructions of casements and transom shown, but only by the scope of the appended claims.

I claim:

1. A mechanism for operating swinging closures comprising a manually operable rotatably mounted threaded shaft, a traveling nut mounted thereon, a lever pivoted intermediate its ends, a short pivoted link connecting one arm of said lever to said traveling nut and means for connecting the other arm of said lever to the swinging closure.

2. A mechanism for operating swinging closures comprising a support, a manually operable threaded shaft rotatably mounted on said support and prevented from endwise movement thereon, a lever pivoted intermediate its ends to said support, a traveling nut mounted on said threaded shaft, a short pivoted link connecting one arm of said lever to said traveling nut and means for connecting the other arm of said lever to the swinging closure.

3. In combination with a door or window frame and a swinging closure therefor, a support concealed within said frame, a manually operable threaded shaft rotatably mounted on said support and having one end thereof extending through an opening in said frame, a traveling nut mounted on said threaded shaft, a lever pivoted to said support intermediate its ends and a short pivoted link connecting one arm of said lever to said traveling nut and means for connecting the other arm of said lever to a swinging closure.

4. In combination with a door frame and a pivotally mounted transom having a crank arm rigidly secured to said transom and concealed in a space of said door frame, a support within said space, a threaded shaft rotatably mounted on said support and held against endwise movement, a traveling nut mounted on said screw, a bell-crank lever pivotally mounted on said support, a short pivoted link connecting one arm of said

lever to said traveling nut and a rod connecting the other arm of said lever to said crank arm, said threaded shaft having one end thereof passing through an opening in 5 the door frame whereby it may be manually rotated to open and close said transom.

5. In combination with a door and a door casing, a concealed mechanism for operating a transom comprising a rotatable shaft concealed in the door frame and having one end thereof extending exteriorly of the same, of a crank having a hub shaft co-acting with said exposed end of said shaft and a crank arm extending into the path of the door in 10 one of the angular positions thereof, said crank arm being pivoted to said hub shaft permitting it to be moved out of the path of the door by engagement with the latter when it occupies the position referred to.
- 15 6. An operating mechanism for swinging closures comprising a manually operated threaded shaft mounted to rotate without endwise movement, a traveling nut on said shaft, a lever pivoted between its extremities and connected at one end with the closure, a link pivoted at one end to the traveling

nut and at the other end to the lever, said link at one end of its travel being substantially parallel to said shaft and at the other end of its travel being angularly disposed 30 with respect to the shaft, whereby the power applied to the closure will be greatest when the link is in its angular position, said angular position occurring when the closure offers the greatest resistance to movement.

7. In combination with a door frame and a pivotally mounted transom having a crank arm connected to said transom for operating the same, a rotatably mounted threaded shaft held against endwise movement, a traveling nut mounted on said shaft, a bell-crank lever, a short link connecting one arm of said lever to said traveling nut, and a rod connecting the other arm of said bell crank lever to said crank arm.

In witness whereof, I subscribe my signature, in the presence of two witnesses.

OSCAR C. RIXSON.
